GARMENT

Charles E. Oathout, Shaker Heights, Ohio, assignor to The Kaynee Company, Cleveland, Ohio, a corporation of Ohio

Application April 3, 1933, Serial No. 664,072

4 Claims. (Cl. 2—265)

The present invention relates to a garment of strength and wear-resisting structure, and, more particularly, to children's garments having reinforcing means for retaining buttons and the like.

5 In the manufacture of articles of children's apparel, such as boys' blouses, difficulty is experienced in so attaching buttons or other fastening means that these will not be pulled or torn from the garment within a reasonable period by 10 the hard usage to which children's clothing is subjected. It is, accordingly, an object of the present invention to provide a garment having improved means for retaining fastening means thereon. A further object of the invention is to 15 provide a garment having a reinforcing element which securely engages buttons and the like. To the accomplishment of the foregoing and related ends, said invention, then, consists of the means hereinafter fully described and particularly 20 pointed out in the claims.

The annexed drawing and the following description set forth in detail certain structure embodying the invention, such disclosed means constituting, however, but one of various structural forms in which the principle of the invention 25 may be used.

In said annexed drawing:

Fig. 1 is a view of a section of a blouse embodying the improved construction; Fig. 2 is a 30 fragmentary view on an enlarged scale of the reinforced construction of the invention; Fig. 3 is a view similar to Fig. 2 but taken from the opposite side of the garment; Fig. 4 is a section taken along the line 4, 4 of Fig. 2 and Fig. 5 is 35 a section taken along the line 5, 5 of Fig. 2.

Referring to the drawing, a section 6 forming a front half of a blouse, for example, is provided with a facing 7 along the finished edge 8 of the garment. This facing is turned under at either 40 side, as shown in Figs. 2 and 3, and is sewed to the under side of the garment by lines of stitching 9 and 11. Within one of the folds, such as fold 12, is enclosed a piece of strong cord 13 which may extend the full length of the garment 45 or be co-terminous with the portion carrying buttons. The cord 13 is securely enclosed in the facings 7 when this latter is sewed to the piece 6 by means of the rows of stitching 9 and 11.

Buttons 14 or fastening means intended for 50 holding the garment on the body of the wearer are attached to the garment by loops of thread 15 passing through the usual holes in the buttons and encircling the cord 13. Of course, these loops of thread may be replaced by loops of other 55 forms or constructions as may be found advis-

able without departing from the scope of the invention. Likewise, the buttons may be replaced by other fastening devices used for securing the garment on the wearer, these means being attached in the same manner.

The cord 13 serves as a strong reinforcement running for a considerable length adjacent a surface of the garment and to which a plurality of buttons or other fastening devices may be attached, the strength of the cord being such that 60 the loops of thread 15 cannot pull out of the garment as is the case where such loops are merely passed through the various thicknesses of cloth which may lie under the button. By the use 65 of the present invention, it is practically impossible to tear a button loose from a garment, if a button of proper strength is chosen and sufficient thread used for joining the cord and the button. The cord shown in the drawing may 70 obviously be replaced by other reinforcing materials of proper strength and characteristics, these being disposed in a similar manner to that shown. Also, the cord or other reinforcing means need not necessarily be enclosed in a facing, such 75 as the facing 7, but may be otherwise attached to the garment, but the construction shown is preferred due to the fact that the cord is not only firmly secured in place by the folded facing, but is also covered over to present a pleasing and uniform appearance in the finished garment. It will be noted that the cord is on the 80 opposite side of the garment from the button or other fastening means, so that the garment is secured between the cord and the button.

Other modes of applying the principle of my 90 invention may be employed instead of the one explained, change being made as regards the structure herein disclosed, provided the means stated by any of the following claims or the equivalent of such stated means be employed.

I therefore particularly point out and distinctly claim as my invention:

1. In a garment, a facing, a reinforcing member enclosed in said facing and securely fastened therein, fastening means for holding said garment on the body of the user positioned opposite said facing, and loops passing through said fastening means and encircling said reinforcing member.

2. In a garment, a facing, a cord enclosed in 105 said facing and securely sewed therein, buttons positioned along said facing on the opposite side of said garment, and loops of thread passing through said buttons and encircling said cord.

3. In a garment, a facing, a cord enclosed in 110

said facing and running the length of one dimension of the garment, buttons positioned adjacent said cord along said facing on the opposite side of said garment, and loops of thread 5 passing through the respective buttons and enclosing said cord.

4. In a garment, a facing, a cord enclosed in

said facing throughout its length and securely sewed therein, buttons positioned along said cord on the opposite side of the garment thereto, and loops of thread passing through a button and enclosing said cord.

CHARLES E. OATHOUT.
